CLAIM

The ornamental design for a pennant display case, as shown and described.

DESCRIPTION

FIG. 1 is a front elevational view of a pennant display case showing my new design;

FIG. 2 is a left side elevational view thereof;

FIG. 3 is a right side elevational view thereof;

FIG. 4 is a bottom plan view thereof, the top view being a mirror image thereof; and,

FIG. 5 is a cross sectional view taken on line 5—5 of FIG. 1.
